[57] ABSTRACT

A system for handling and distributing fluid is disclosed, which system is particularly useful for handling and distributing coating materials utilized in applying a thin metallic oxide coating to the outer surface of glass containers. The system includes readily accessible and replaceable bulk storage, preferably including a plurality of receptacles such as storage barrels, which receptacles are caused to selectively and successively supply fluid (which fluid may be chemicals such as titanium tetrachloride, tetraisopropyl titanate, or tin tetrachloride, for example, where a metallic oxide coating is to be applied to a newly formed glass container) to a reservoir which in turn has the fluid pumped therefrom and supplied to a remotely located master tank. The master tank is connected to the reservoir in a manner to maintain a substantially constant fluid level therein, and level monitoring apparatus is provided in the master tank. One or more slave tanks are connected with the master tank and each is maintained at a predetermined fluid level with respect to the master tank. Each slave tank is preferably adjacent to and is connected with a utilization station, which station is an article coating station where newly formed glassware is to be coated with a thin metallic oxide coating. The system is automatic in normal operation and indications of deviations in fluid level of the master tank beyond both predetermined minimum and maximum levels are provided by the monitoring apparatus and normal operation is then terminated.

FLUID HANDLING AND DISTRIBUTING SYSTEM

BACKGROUND OF THE INVENTION

1. Field of the Invention

The present invention relates generally to a fluid handling and distributing system and more particularly to a system for handling and distributing coating materials used in applying a thin metallic oxide coating to the outer surface of glass articles.

2. Description of the Prior Art

It is oftentimes necessary, or at least desirable, to provide a tank or other receptacle for a particular fluid at a utilization station. Such a need can occur, for example, in the production of glass containers where a protective coating is commonly applied to the surface of a newly formed container while the container still retains sufficient heat from formation to cause a metallic oxide coating to be formed on the surface of the container when the container is exposed to fluid which includes a heat decomposable metallic compound. Where such a metallic oxide coating is to be applied to a glass container, such a fluid normally comprises a gas inert to the coating material, such as dry air, and a heat decomposable metallic compound, which may be formed by injecting dry air into the bottom portion of a tank containing the coating material and allowing the air to pass upwardly through the coating material. As a result, a vapor including the coating material is expelled from the tank under pressure and introduced into the article coating station, commonly a hood or other enclosure, and articles to be coated are then passed through the hood. Treatment of glass articles to coat the same by introducing a vapor into a hood is shown, for example, in U. S. Pat. No. 3,615,327, while the formation of a vapor that includes a metallic coating compound as coating material is shown, for example, in U. S. Pat. Nos. 3,561,940 and 3,516,811.

In forming a vapor suitable for applying a thin metallic coating to glass articles as described hereinabove, it has been found to be necessary and/or at least desirable to provide a closed system to maintain the level of coating material in the tank within certain predetermined limits. A closed system is important since, as brought out in U. S. Pat. No. 3,615,327, at least some of the metallic vapors utilized (and hence presumably the coating materials) are stated to be corrosive in nature, and, moreover, each opening of the system (as necessary for replenishing of coating material) can allow entrance of unwanted moisture. Level maintenance of coating material in the tank is also important since the level of coating material will, at least in part, determine the amount of coating material included in the resulting vapor produced where such a vapor is produced by passing the inert gas upwardly through the liquid coating material.

Heretofore, it has been a common practice to provide a separate unit for supplying each article coating station and manually monitoring each unit to determine when necessary to replace and/or refill the same. In addition, while reclaiming of treating material with subsequent reintroduction into a supply receptacle has heretofore been suggested for usage, vapors exhausted from article coating stations are often not so utilized, and automatic maintenance of the level of coating or treating material has not been utilized in such known systems. Likewise, apparatus for monitoring the level

of one or more tanks of coating material to guard against unwanted level deviations have not been found in prior handling and distributing systems of this type.

SUMMARY OF THE INVENTION

This invention provides a closed system for handling and distributing fluids that is simple and inexpensive, yet is dependable, and provides both level maintenance and automatic fluid supply, as well as automatic level monitoring.

It is therefore an object of this invention to provide a simple and inexpensive, yet dependable, system for handling of fluids.

15 Another object of this invention is to provide a system that is suitable for automatically providing coating material in liquid form to one or more article coating stations from a supply source that may be remotely situated for convenience.

20 It is yet another object of this invention to provide a system for handling and distributing fluids that automatically maintains a desired level at one or more tanks each of which is associated with a utilization station.

25 It is still another object of this invention to provide a system for handling and distributing coating material in liquid form that is suitable in providing a common reservoir of such coating material and supplying the same to one or a plurality of coating stations with the liquid level at each station being automatically maintained relatively constant.

30 It is still another object of this invention to provide a system for handling and distributing coating material that includes as part of the supply source, a plurality of storage receptacles that are automatically selectively connected with a reservoir supplying coating material to one or more article coating stations.

35 It is still another object of this invention to provide a system for handling and distributing fluids that includes automatic level monitoring.

40 With these and other objects in view which will become apparent to one skilled in the art as the description proceeds, this invention resides in the novel construction, combination, and arrangement of parts substantially as hereinafter described and more particularly defined by the appended claims, it being understood that such changes in the precise embodiment of the herein disclosed invention are meant to be included as come with the scope of the claims.

DESCRIPTION OF THE DRAWINGS

The accompanying drawings illustrate a complete embodiment of the invention according to the best mode so far devised for the practical application of the principles thereof, and in which:

55 FIG. 1 is a flow diagram, in block form, of the system of this invention showing utilization at a plurality of article coating stations;

60 FIG. 2 is a perspective view of the device of this invention as shown in block form in FIG. 1, but detailing utilization of only one of a possible plurality of slave tanks;

65 FIG. 3 is a side sectional view taken across the reservoir and showing the connections thereto of a plurality of bulk storage tanks;

FIG. 4 is a partial side view of the bulk storage tanks and end view of the reservoir of the coating material storage supply of this invention;

FIG. 5 is a side view of a level control that may be utilized in the master tank of the system of this invention; and

FIG. 6 is an electrical schematic diagram of the control circuit of the system of this invention.

DETAILED DESCRIPTION

Referring now to the drawings, in which like numeral have been used for like characters, the numerals 11 and 12 in FIGS. 1 through 4 refer to the fluid bulk, or coating material supply source, which is shown in FIGS. 2 and 3 to consist of a plurality (two as shown) of barrels, or drums, of coating material. The coating material, when utilized for applying a coating to the surface of glass articles is normally a heat decomposable metallic compound in liquid form, such as, for example, titanium tetrachloride, tetraisopropyl titanate, or tin tetrachloride, all of which are commercially available.

The coating material receptacles 11 and 12 are connected by lines, or conduits, 14 and 15, respectively, to a reservoir 17, which reservoir is automatically maintained filled with liquid coating material from the supply source as described in greater detail hereinafter. Reservoir 17 is, in turn, connected through line 18 to an electric pump 20, which pump pumps coating material through line 21 to master, or main, tank 23.

Master tank 23 has a level indicator 24 therein, the electrical leads from which are conducted through conduit 25 to alarm circuitry 27 which has connected therewith alarm indicator 28. This apparatus monitors the level in the tank and indicates any level deviation beyond a predetermined maximum or minimum level. Master tank 23 has connected therewith through a line 30, one or more slave tanks, indicated in FIG. 1 as a plurality of four slave tanks 32, 33, 34, and 35. As shown in FIG. 2, only slave tank 32 has been detailed, but it is to be appreciated that a plurality of slave tanks, as indicated in FIG. 1, may be utilized if found necessary or convenient. Master tank 23 and the slave tanks associated therewith may be of the same size and may be connected by three-fourths inch lines (as may reservoir 17 also be connected to master tank 23). In a working embodiment, it was found that tanks with a diameter of about one foot and a height of about 28 inches (about 12½ gallon capacity) were operationally satisfactory.

Slave tank 32 is connected through line 37 to associated article coating station 42, while, as shown in FIG. 1, slave tanks 33, 34, and 35 may be connected in like manner through leads 38, 39, and 40, respectively, to associated article coating stations 43, 44, and 45, respectively. Article coating stations 42 through 45 have not been shown in detail herein, it being understood that each of these stations may include a hood (not shown) into which vapor that includes heat decomposable metallic coating compound is introduced to coat glass articles with a thin coating of metal oxide as they pass through the hood while the articles retain heat of formation above the decomposition temperature of the heat decomposable metallic compound utilized. Article coating stations of this type, as well as stations utilizing a tank of coating material through which an inert gas (such as dry air) is passed to supply the needed vapor that includes the coating material are known in the prior art and examples of such prior art have been set forth hereinabove and should be consulted for a description in greater detail, if needed.

In a working embodiment of this invention, stainless steel and/or Teflon components were used throughout and along with welded joints provided a satisfactory closed system.

5 Referring now to FIG. 2 of the drawings, the coating material supply is shown to include barrels, or drums, 11 and 12. These drums may be conventional and the material to be utilized is stored therein, preferably in liquid form. Such material may, for example, be titanium tetrachloride, tetraisopropyl titanate or tin tetrachloride, as brought out hereinabove, where the coating material is to be utilized for the coating of glass containers. The barrels, or drums, 11 and 12 are preferably easily removable for supply replenishment and other 10 purposes, and accordingly, are mounted on U-shaped support frame 47 the legs 48 of which have wheels 49 conventionally mounted near the free ends and the central portion of which has a wheel 50 conventionally pivotably mounted thereon. Upstanding supports 52 extend from frame 47 rearwardly of wheels 49 and the free ends of supports 52 are conventionally secured to the sides of the associated barrel (11 or 12) at 53 so that the barrels may pivot in a vertical plane to facilitate 15 connection to reservoir 17 and/or emptying or cleaning of the barrel. To provide stability of operation, the lower rear portion of the barrel can rest on the top of frame 48 above wheel 50 (and could, of course, be blocked conventionally at any desired angle).

20 Barrels 11 and 12 are operationally positioned adjacent to reservoir 17, as shown best in FIG. 2, so that each barrel can be connected with both an outlet line (14 or 15) and with an air return.

25 The air return to each of the barrels 11 and 12 is provided by means of a partial double conduit. As shown in FIG. 2, air return 56 for barrel 11 has conduit 57 connected to barrel 11 and parallel connected conduits 58 and 59 connected between reservoir 17 and conduit 57, the latter connection being achieved through a 30 valve 60 which connects conduit 57 to either conduit 58 or 59 depending on valve positioning (this valve could also be utilized to disconnect conduit 57 from both conduits 58 and 59 and eliminate the unnumbered 35 separate shut-off valve indicated in conduit 57 near the top of barrel 11).

40 Conduit 58 is connected with reservoir 17 by means of coupling, or fitting, 62 which extends into the reservoir 17 a short distance, preferably about one inch. Fitting 61, which connects conduit 59 with reservoir 17 45 opens only into the top of the reservoir and does not extend downwardly therein, as best shown in FIG. 3.

45 In like manner, the second barrel 12 is likewise connected with the reservoir. As shown in FIGS. 2 and 3, air return conduit 64 includes conduit 65 connected to the top portion of barrel 12 through an unnumbered 50 shut-off valve, while conduits 66 and 67 connected in parallel, are connected to reservoir 17 and to conduit 65 through valve 68. Valve 68, like valve 60 may be utilized to open conduit 65 to either of conduits 66 and 67 or to neither of them. Fitting 69 does not extend into reservoir 17 and opens conduit 67 to the top of the reservoir while fitting 70, like fitting 62, extends into reservoir 17 a short distance, preferably about 1 inch. If desired, fittings 61 and 69 may also extend into the reservoir a short distance, and if this occurs, fittings 62 and 70 must extend further into the reservoir by about 55 1 inch than do fittings 61 and 69.

In addition to the inlets to and outlets from the top of reservoir 17 to the supply drums 11 and 12, an air supply line 72 is also connected to reservoir 17 by means of a fitting 73 which opens the air supply line into the top of the reservoir. Line 72 is connected with a pressurized source (not shown) so that a small pressure is maintained within the reservoir. This may be readily accomplished by connecting line 72 to a source of dry air (i.e., air dried to a very high degree, such as to a dew point of -50° F. or more) having a pressure of not more than about 1 pound per square inch (1 p.s.i.).

As shown in FIGS. 2 through 4, reservoir 17 includes an elongated cylindrical body portion 75 both ends of which are closed by end plates 76 (front) and 77 (rear). Reservoir 17 is sized and positioned with respect to the bulk source utilized (barrels 11 and 12 as shown) so that the reservoir can remain filled with liquid by gravity feed from the storage source to the reservoir. As shown in FIGS. 2, 3, and 4, this positioning arrangement is preferably with the top of the reservoir about level or just below the bottom of barrels 11 and 12. In a working embodiment of this invention, two conventional 55 gallon drums were utilized as storage barrels 11 and 12 and a reservoir of about 15 inches diameter and a length of about 6 feet was satisfactory to give the desired performance. The reservoir (and conduits), must of course, be sized to handle the expected maximum flow of coating material and positioned in view of known factors such as atmospheric pressure differentials to be encountered.

The air returns 56 and 64 from reservoir 17 to the drums 11 and 12 provide an automatic feed selection arrangement. Since the barrels are connected to a double conduit return, an operator, after initially connecting two barrels filled with coating material to the reservoir, turns valve 60 (for example) to connect reservoir 17 with conduit 59 and turns valve 68 to connect reservoir 17 with conduit 66. Since conduit 59 is connected with the top of the reservoir while conduit 66 is connected with fitting 70 which extends into the barrel, the reservoir is filled from drum 11 since an uncovered air return is provided through conduits 57 and 59, while the air return conduit 66 is effectively closed since fitting 70 extends into the liquid in the filled barrel to preclude a return of air to drum 12. This arrangement causes the coating material from drum 11 to be gravity fed into the reservoir to keep the reservoir full until drum 11 is empty. After drum 11 empties and the level of coating material in the reservoir drops to a point sufficiently low to expose the lower end of fitting 70, air is then permitted to return to drum 12 and this drum would then be emptied into the reservoir to maintain the reservoir at a level roughly equal to the bottom of fitting 70 extending into the drum (preferably about 1 inch). An operator would then avoid depletion of the coating material supply by connecting a new barrel in place of barrel 11 (or by filling barrel 11). At this time, the operator would preferably change valve 68 to connect barrel 12 through conduit 67 (which would then allow the reservoir to completely fill since conduit 67 opens into the top of reservoir 17) and changes valve 60 so that conduit 58 is connected with the barrel (which conduit is connected to fitting 62 which extends down into the barrel) so that the contents of barrel 11 would not then feed into the reservoir until barrel 12 was empty. While not shown, a level indicator could be

conventionally mounted in barrels 11 and 12 to facilitate manual monitoring of the barrels in conventional manner. If fittings 61 and 69 extend into the reservoir so that fittings 62 and 70 extend into the reservoir about 1 inch further than do fittings 61 and 69, the level in the reservoir will, of course, at no time be higher than the shortest of these fittings. Operation will be unaffected, however, and such an arrangement may often be preferred.

Reservoir 17 is connected to conduit 18 through fitting 79 which opens from the bottom of the reservoir through front end plate 76. The outlet conduit is connected to pump 20, as shown in FIG. 2, and if desired a shut-off valve can be inserted into the line, as indicated in FIG. 2. Pump 20 is preferably utilized in a constantly energized state during normal operation to thus maintain a constant flow of material between the main tank 23 and the reservoir 17. The inflow to main tank 23 is maintained through conduit 21 from the pump 20 into the bottom portion of the main tank 23 through fitting 83. A return conduit 80 is connected to reservoir 17 from main tank 23 with the return being connected to reservoir 17 at the top center thereof through fitting 81, and the return conduit is connected to the upper portion of the main tank 23 by means of fitting 84, as shown in FIG. 2. Fitting 84 for return conduit 80 preferably opens into main tank 23 a short distance downwardly from the top of the tank so that a level control can be inserted into the tank as is brought out more fully hereinafter. It is found that with a level control as shown in FIG. 5, the return conduit preferably opens into main tank 23 about nine inches below the top of the tank.

The coating material from the main tank to the slave tanks is fed through conduit 30 connected to the main tank by means of fitting 85 which opens into the bottom portion of the main tank as shown in FIG. 2. A shut-off valve can also be inserted into this line if desired. In addition, the top of main tank 23 has an aperture to receive a fitting 86 therein which allows insertion of a level indicator such as level indicator 24 shown in FIG. 5. The electrical connection of the level control indicator 24 is by means of a plurality of wires leading from switches in the level control unit. These wires (four as shown in FIG. 6) are conducted through conduit 25 to the alarm circuitry 27, as is brought out more fully hereinafter (conduit 25 can, of course, be eliminated and the wires conducted to the alarm circuitry without additional covering if desired).

As is shown in FIG. 2, slave tank 32 (this being the only slave tank detailed in FIG. 2 although it is to be appreciated that additional identical slave tanks, such as slave tanks 33, 34, and 35, may be utilized as brought out hereinabove) is connected to conduit 30 at the bottom portion thereof by means of fitting 88 so that when the master tank 23 is connected with one or more slave tanks by conduit 30 as an open line, the connected slave tanks are gravity fed from the master tank and hence will fill to a predetermined level determined by the relative positioning of each slave tank with respect to the master tank. If, as preferred, the slave tanks utilized are positioned at the same level as the master tank, then the slave tanks will fill to the same level as the master tank by gravity feed. Each slave tank may, if desired, have a shut-off valve which can be closed, as can conduit 30, as indicated in FIG. 2.

As also shown in FIG. 2 slave tank 32 has an air inlet at the top of the tank with conduit 90 leading from a pressurized air supply source (not shown) to fitting 91 with the fitting extending into the bottom portion of the tank as indicated in FIG. 2. Dry air is conventionally injected into the slave tank (preferably at about 10 p.s.i. or less) and bubbled therethrough so that vapor laden with coating material may thereafter be conducted from the slave tank through conduit 37 to the article coating station for applying a thin coating to glass articles as is described in greater detail hereinabove.

Referring now to FIG. 5, a level control is shown which can be utilized with the system of this invention to provide an indication of level deviations in the master tank beyond predetermined minimum and maximum levels. As shown, a shaft, or tube, 96 extends downwardly into the main tank and may be secured to the top thereof by a shaft connector 97 to the bottom of the mounting plug, or fitting, 86. A shaft end fitting 98 is conventionally secured to the bottom of shaft 96 to seal the same, while a plurality of shaft unions 100, 101, and 102 are spaced along the shaft, as shown in FIG. 5. Obviously shaft 96 could also consist of a plurality of short tubes connected between the tube unions and tube ends in conventional fashion if desired. Shaft 96 is preferably one-half inch diameter tubing and the entire length of the level indicator below fitting 86 is about 16 inches.

A conventional level responsive switching station 104 is received on shaft 96 with the station being constrained to movement axially along the shaft between unions 100 and 101. Station 104 is preferably nearly spherical in shape, as shown in FIG. 5, and, when in position on the vertically extending shaft 96, will normally assume a position with the lower end in engagement with union 101 due to the downward pull of gravity. Station 104 is buoyant, however, as by being air filled or of floatable material, so that the station 104 will be moved upwardly when the liquid level rises sufficiently to overcome the force of gravity. As shown, station 104 can be moved upwardly due to a rise in the liquid level within the master tank until the top of the station is in engagement with union 100. As indicated in FIG. 6, station 104 includes a switch which is open when the station is in one position relative to the shaft and closed when in a second position. As indicated in FIG. 5, the switch is normally closed when the station is contiguous to union 101 and open when displaced upwardly by the liquid level in the tank so as to be contiguous to union 100.

In like manner, a conventional level responsive switching station 105 is received on shaft 96 with the station being constrained to axial movement along the shaft between shaft end fitting 98 and union 102. Station 105 is identical to station 104 and, when positioned on shaft 96, assumes a position, due to gravity, with the bottom portion in engagement with end fitting 98 except when displaced upwardly due to the liquid level in the tank, the limit of upward movement of station 105 being with the top portion of the station in engagement with union 102. Like station 104, station 105 also includes a switch which is open when the station is in one position relative to the shaft and closed when in a second position. As indicated in FIG. 5, the switch is normally closed when the station is displaced upwardly due to liquid within the tank so as to be contiguous

to union 102 and open when the liquid level falls sufficiently to allow the station to drop downwardly along the shaft so as to be contiguous to end fitting 98.

Since station 104 is the uppermost station of the pair of stations when positioned in master tank 23, this station senses a liquid level that is predetermined to be higher than, or at least at a maximum height level, desired within the tank, while the lower station 105 senses a drop in liquid level to a level at least equal to a minimum acceptable level, or lower. In normal operation, the liquid level is maintained between stations 104 and 105 (the outlet from master tank 23 at fitting 84 is preferably midway between the stations) so that station 105 is normally immersed in liquid and hence is held in its uppermost position, while station 104 is normally above the liquid level and hence is normally in its lowermost position, as is indicated in FIG. 5. Stations 104 and 105 may preferably be displaced a maximum of about one-half inch upwardly or downwardly on shaft 96 to change the state of the switch associated with each, and during normal operation each station (which has a diameter of about 2 inches) is maintained about $3\frac{1}{2}$ inches from the normal fluid level in a working embodiment of this invention. Other level indicators could, of course, be utilized in this invention, if desired, it being only important that the fluid level be sensed and at a predetermined point an indication thereof produced, such as a switch being caused to change states (between open and closed positions).

Both stations 104 and 105 have leads extending from the switches therein (as indicated in FIG. 6) and these leads are conducted upwardly through shaft 96 (not shown) and out of the master tank through fitting 86 and conduit 25 to the alarm circuitry 27. As indicated in FIG. 2, alarm circuitry 27 is located at main panel 107. Main panel 107 is connected with an auxiliary, or field, panel 108, preferably located near the storage supply which, as brought out hereinabove, may be preferably remotely located with respect to the tanks and coating stations. A conduit 109 is shown connecting the two panels and it is to be understood that the necessary leads may be conducted therethrough to accomplish the electrical wiring arrangement as set forth in FIG. 6. The panels, both main and field, show a plurality of switches and lights (not numbered), and it is to be understood that this is merely a representation of placement to carry forth the electrical embodiment more specifically detailed in FIG. 6.

Referring now to FIG. 6, the electrical schematic diagram of the system is shown. As can be appreciated, the only electrical circuitry required in the system is for motor control, the remainder of the electrical system being for automatic level monitoring.

Power for the system is conventionally supplied from a 110 volt AC, 60 cycle source (not shown) through leads 111 and 112. Fuses 113 and 114 are supplied in the line with fuse 113 being connected to lead 116 and fuse 114 is connected to line 117. Line 116 is connected through main power switch 118 to line 119 so that the main power lines for the circuit consists of lines 117 and 119. Lead 120 connects line 119 to one side of field power on light 121 (the other side of which is connected to line 117 by lead 122) and to one side of power on light 123 (the other side of which is connected to line 117 by lead 124). As indicated in FIG. 6, these lights are preferably amber in color, and power

on light 123 is on the main panel 107 while field power on light 121 is on the auxiliary, or field, panel 108.

Lead 125 connected connects one side of test switch 126 to lead 119, while lead 127 connects the other side of the test switch to a plurality of components including a connection to one side of pump on light 128 (the other side of which is connected to line 117 through lead 129). Pump on light 128 is at the main panel and is preferably green, as indicated in FIG. 6. Lead 131 connects line 119 to one side of field stop switch 132, the other side of this switch being connected by lead 133 to one side of stop switch 134. Both stop switches 132 and 134 are normally closed with stop switch 134 being located on the main panel 107, while field stop switch 132 is located on the auxiliary panel 108. Stop switch 134 is connected by lead 135 to field start switch 136, main start switch 137, and one side of switch 138, all of which are normally open with switches 136 and 137 being on the auxiliary and main panels, respectively. Switch 138 is connected in series with normally open switch 139, with switches 136, 137, and 139 being connected to lead 141 which is also connected to lead 127. One side of pump motor controller 142 is connected to lead 141 (the other side of which controller is connected to lead 117 through lead 143). In addition, one side of field pump on light 144 is likewise connected to lead 141, while the other side is connected to lead 117 through lead 145. Field pump on light 144 is located at the auxiliary panel 108 and is preferably green in color, while pump motor controller 142 is an AC control relay that controls actuation of switches 138 and 147.

Lead 146 connects one side of normally open switch 147 to line 119, while the other side of switch 147 is connected by lead 148 to motor 150 of pump 20, with the other side of the motor being connected to line 117 through lead 151. Lead 152 connects lead 119 to one side of normally closed switch 153 with the other side being connected through lead 154 to fluid level alarm light 155, the other side of which is connected through lead 156 to lead 117. Fluid level alarm light 155 is preferably red in color and is located near the main panel 107 (this light is indicated in FIG. 2 as light 28). This alarm indicator could, of course, also include a bell or other indicator as desired.

Lead 157 connects lead 119 to the center input of a conventional single pole double throw (SPDT) switching arrangement 158 indicated in block form in FIG. 6. This switching arrangement includes leads 159 and 160 which are connected to high fluid level switch 161 within high level fluid sensing station 104 (leads 159 and 160 thus extend from station 104 to panel 107 through conduit 25). The state of switch 161, which state is determined by the positioning of station 104 on shaft 96, thus determines which of the two outputs of switching arrangement 158 will be connected with lead 157. One output from switching arrangement 158 is connected by lead 162 to the field high fluid level light 164 (the other side of which is connected by lead 165 to line 117) and to high fluid level light 166 (the other side of which is connected by lead 167 to line 117). These lights are preferably red in color and are located in the main (light 166) and auxiliary (light 164) panels. The other output from the switching arrangement 158 is taken through lead 168 to the center input of a second conventional single pole double throw (SPDT) switching arrangement 186. Like switching arrange-

ment 158, switching arrangement 186 has leads 169 and 170 connected to the level indicator 24, with leads 169 and 170 extending through conduit 25 and shaft 96 to low fluid level switch 171 within low level fluid sensing station 105. The state of fluid level switch 171 depends on the positioning of station 105 on shaft 96, and the state (either open or closed) of switch 171 determines which output from the switching arrangement will be connected with lead 168. One output from switching arrangement 186 is connected by lead 173 to one side of field low fluid level light 174 (the other side of which is connected through lead 175 to line 117) and to one side of low fluid level light 176 (the other side of which is connected by lead 177 to line 117). These lights are preferably red in color and are found at the main (light 176) and auxiliary (light 174) panels. The other output from the switching arrangement 186 is taken through lead 178 to controller 180 the other side of which is connected to line 117. Controller 180 is an AC contactor which controls the state of switches 139 and 153.

In operation, power is applied to the system by actuating power switch 118 from an off position to an on position. This will energize the power on lights to show that power is available at the system. If desired, test switch 126 can then be actuated to the on position to energize pump on lights 128 and 144 and energize pump motor controller 142 to close switch 147 and thereby energize pump motor 150. Actuation of the test switch 126 to the off position will then de-energize the pump on lights and controller to thus de-energize the motor. If the liquid level is below the predetermined minimum level as established by the position of station 105 of the level indicator 24 within master tank 23, switch 171 will be open and controller 180 will remain de-energized when power is applied. This will cause switch 153 to be in the normally closed position and will thus allow fluid level alarm 155 to be energized until the level is brought up sufficiently in the master tank to close the switch and energize controller 180 to open switch 153 and de-energize the alarm.

To start the pumping operation, it is necessary to close either start switch 137 or field start switch 136 to energize pump motor controller 142 and thus close switch 147 to energize the pump motor 150. Pump motor control 142 will not remain energized, however, if the start or field start button is opened prior to the time that the liquid level rises sufficiently in the master tank to cause the low fluid level switch 171 to be actuated from a low level indication. Only after switch 171 has been actuated from a low level indication is it possible for controller 180 to be energized to close switch 139 and establish a holding circuit around the start switches (switch 138 is closed by energization of controller 142). Pump 150 will then remain energized so long as the pump motor controller 142 remains energized. In normal operation, the pump will constantly pump coating material into the master tank and the level will remain constant with the excess over that utilized at the slave tanks being returned to the reservoir 75 via the return line 80 (the return line opens into the master tank about mid-way between the high and low level sensing stations 104 and 105).

Termination of pump energization can occur by power disruption to the system, by actuating the power switch 118 to the off position, or by opening either stop switch 132 or 134. In addition, automatic termination

of pump energization will occur if the liquid level in the main tank should either rise or fall to a level to change the state of either switch 161 (high level) or switch 171 (low level). If this should occur, controller 180 will be de-energized and this will close switch 153 to actuate the alarm 155 and open switch 139 to de-energize pump motor controller 142 and hence open switch 147 to stop the pump motor 150. If the high level switch 161 is actuated, controller 180 is de-energized by terminating the power thereto and power is applied to the high fluid level lights 164 and 166. If the low level switch 171 is actuated, controller 180 is likewise de-energized by terminating the power thereto, but in this event power is applied to the low fluid level lights 174 and 176. After the problem with respect to fluid level in the master tank has been corrected, then normal operation can be resumed by actuating the start or field start switches. A high level could occur, for example, due to a blocked return line to the reservoir, while a low level could occur, for example, due to a lack of supply of coating material.

As can be seen from the foregoing, the system of this invention provides a heretofore unavailable means for handling and distributing fluids that is particularly useful in handling and distributing coating materials for use in coating glass articles.

What is claimed is:

1. A liquid handling system, comprising: a slave tank for supplying liquid to utilization means; a master tank; conduit means for connecting said slave tank to said master tank, said slave and master tanks being positioned so that predetermined relative liquid levels exist therebetween when said conduit means is open between the slave and master tanks; a storage reservoir including a reservoir tank and a plurality of bulk storage tanks, air return means connecting said reservoir tank and the plurality of bulk storage tanks, said air return means having selectable first and second parallel conduits with a first conduit extending into said reservoir tank a greater distance than does the second conduit so that a first bulk storage tank with a first conduit selected is precluded from supplying liquid to said reservoir tank until the liquid level falls below said first conduit extending into said reservoir tank, while a second of said bulk storage tanks with said second conduit selected will continuously provide liquid to said reservoir tank and preclude liquid supply from the first of said bulk storage tanks until the second of said bulk storage tanks is empty.

2. The liquid handling system of claim 1 wherein said master tank has a level monitoring means therein, and wherein said system includes an alarm indicator connected with said level monitoring means and indicating master tank liquid level deviations beyond predetermined minimum and maximum levels.

3. A fluid distributing system, comprising: a reservoir; first and second storage tanks; first and second conduits connecting said first and second storage tanks to said reservoir; and first and second air return means connecting said reservoir to said first and second storage tanks, said air return means including means for preselecting and causing automatic successive supply-

ing of fluid from said storage tanks to said reservoir.

4. The fluid distributing system of claim 3 wherein each of said air return means includes first and second air return conduits connected in parallel with one another, said first air return conduit extending into said reservoir a greater distance than does the second, and wherein each of said air return means includes a valve for selecting which of said first and second air return conduits are connected with said associated storage tank.

5. A liquid handling system for coating material used in applying a coating to glass articles, said system comprising: a slave tank for supplying coating material in liquid form to coating material utilization means; a master tank; conduit means for connecting said slave tank to said master tank, said tanks being positioned so that a predetermined relative liquid level of coating material exists therebetween when said conduit means is open between the tanks; a coating material storage reservoir; and means for connecting said storage reservoir to said master tank so that coating material in liquid form is supplied from said reservoir to said master tank to maintain the level of coating materials in said master tank substantially constant during normal operation of the system.

6. A liquid handling system for coating material used in applying a coating to glass articles, said system comprising: a plurality of glass article coating stations for receiving glass articles to be coated with a predetermined coating material; a plurality of slave tanks equal in number to said article coating stations with each said slave tank being associated with a different one of the said article coating stations to supply coating material thereto; a plurality of first conduits for connecting each of said slave tanks to an associated coating station; a master tank; second conduit means for connecting said master tank with said slave tanks, said tanks being positioned so that when open to one another through said second conduit means said tanks attain a predetermined level of coating material relative to one another; a reservoir of coating material; third and fourth conduits connecting said master tank with said reservoir, said conduits opening into said master tank at predetermined vertically spaced positions; a pump connected with said third conduit to cause coating material to be constantly pumped to said master tank and the excess then returned to said reservoir; a plurality of bulk storage tanks; a plurality of fifth conduits for individually connecting each of said bulk storage tanks to said reservoir; a plurality of sixth conduits for individually providing an air return to each of said bulk storage tanks from said reservoir, each of said sixth conduits including means to cause automatic successive supplying of coating material to said reservoir to maintain the fluid level therein at predetermined levels; a level sensing device in said master tank; and indicator means connected with said level sensing device to indicate level deviations beyond a predetermined minimum level and a predetermined maximum level and to terminate pump operation should said predetermined levels be reached.
